UNITED STATES PATENT OFFICE.

PHILIP C. WAITE, OF OSHKOSH, WISCONSIN, ASSIGNOR TO WAITE CARPET COMPANY, OF OSHKOSH, WISCONSIN, A CORPORATION OF WISCONSIN.

RUG AND STRAND THEREFOR.

Application filed March 23, 1927. Serial No. 177,519.

In the making of rugs of a certain class, it is at present common to employ strands composed of fiber, which are subject to certain objections which the rug of the present invention is designed to avoid. All-fiber rugs tend to soil easily and are very hard to clean, and, at the same time, the fiber surface affords a somewhat hard or unyielding surface which lacks the warm texture 10 luster, and other desirable characteristics of a wool surfaced rug. At the same time, the character of the fiber is such that it can be readily and satisfactorily decorated by a stencil pattern, since the colors tend to adhere to the fiber surface in such a way as to afford a pleasing or attractive stencilled pattern which is not the case with a wool surfaced rug.

The present invention is designed to obviate the objections above noted by the use of strands composed of a fiber core with a spiral open wrapping of wool yarn which affords a contrast in appearance between the exposed fiber core and the wool wrapping, thereby giving a mottled or variegated surface appearance, and also a surface texture which is much more pleasing and possesses a better "feel" than a rug composed entirely of fiber. Furthermore, the exposure of the fiber core between the wool wrappings permits the use of stencil patterns, and the wool surface not only serves in a measure to protect the fiber against both soil and wear, but also cleans more readily, although the mottled or variegated exposed surface tends to conceal or neutralize the effect of soiling, so that the rug from every standpoint is more attractive and desirable than the all-fiber rug.

In the drawing:

Figure 1 is a plan view of a section of the rug comprising the features of the present invention; and

Fig. 2 is an enlarged strand more clearly showing the relation of the wool wrapping to the fiber core.

The strand comprises a core A which is formed by bundling or cabling together a plurality of constituent strips B of fiber or like material intended to constitute the filler for the rug, and adapted to give the required body or substance to it. It is immaterial just how the core itself may be bundled or cabled, provided only that it assumes the desired form to afford a rug strand of the de-

sired thickness, and the core itself may be composed of varicolored constituents, if desired.

Around the core, which is relatively thick and heavy, is a spiral winding C of yarn, composed of wool or other material having the characteristic texture of wool, although wool is preferred in lieu of any substitute therefor. The winding C is relatively thin or light, but it affords an outstanding spiral rib of contrasting texture to the core, the surface of which is relatively hard or harsh in comparison with the softer and fluffy surface of the wool. The core and the winding thus afford not only a contrast in texture, but in appearance, giving to the rug surface a mottled or broken effect, and by reason of the fact that the wool winding outstands from or protrudes above the core filler, it will afford the most conspicuous surface element in the completed rug and gives a characteristic appearance thereto.

The rug, of which a section is shown in Fig. 1, is built up of strands of the character described which constitute the woof strands of the rug, and are secured together by warp strands D of relatively thin and inconspicuous cord which, however, serve not only to bind together the woof strands, but to hold down the wool wrappings against displacement.

In order to afford a pleasing color body tone to the rug, it is desired to employ a wool wrapping affording a contrast in color to the core of each strand, but in addition to this general color effect, it is desired to employ stencil patterns E which may be readily applied on the surface of a rug having the wool surface texture of the present rug, by reason of the fact that the exposed fiber core tends to absorb and hold the stains or pigments which do not readily adhere to an all wool surface, and, at the same time, the upstanding wool surface protects the core against abrasion, which would tend to rub away or wear off the pigment adhering to the core surface. In this way, it is possible to secure permanent stencil designs which cannot readily be applied to all-wool rugs which lack the exposed fiber surface of the present invention, although in the present rug the stencil also covers the wood wrapping.

In view of the fact that the wool wrapping outstands from the core, it will be-

come the most conspicuous surface element in the completed rug, and afford a surface which most intimately comes in contact with the feet, so that both in appearance and 5 in feel, it becomes difficult to distinguish the rug of the present invention from an all-wool surfaced rug save upon close inspection. At the same time, the fluffy texture afforded by the wool wrappings tones down 10 the hard or harsh appearance of the fiber.

The rug is thus much superior to an all-fiber rug from every standpoint in that it 15 presents a more attractive appearance, soils less readily, and is easier to clean. At the same time, the body filler of the rug is composed of fiber, the wool being conserved to afford the surface texture, so that it is possible to secure the characteristics of an all-wool rug at a cost not greatly in excess of 20 that of a cheap fiber rug.

I claim:

1. A rug strand having a core of relatively bulky hard-surfaced fiber-like material, and a relatively lighter open spiral winding of 25 fluffy wool-like material outstanding from and bearing upon the hard-surfaced fiber-like core, the turns of the winding being spaced apart to clearly disclose the hard-surfaced core, substantially as described.
2. A rug strand having a core of relatively bulky hard-surfaced fiber-like material composed of strands thereof bundled together, and a relatively lighter open spiral winding of fluffy wool-like material 35 outstanding from and bearing upon the hard-surfaced fiber-like core, the turns of the winding being spaced apart to clearly disclose the hard-surfaced core, substantially as described.
3. A rug composed of strands each having a core of relatively bulky hard-surfaced fiber-like material, and a relatively lighter open spiral winding of fluffy wool-like material 40 outstanding from and bearing upon the

hard-surfaced fiber-like core, the turns of 45 the winding being spaced apart to clearly disclose the hard-surfaced core, substantially as described.

4. A rug composed of strands each having a core of relatively bulky hard-surfaced fiber-like material and a relatively lighter open spiral winding of fluffy wool-like material outstanding from and bearing upon the hard-surfaced fiber-like core, the rug having 50 a stencil pattern imprinted upon its surface and impregnating the exposed fiber cores, the turns of the winding being spaced apart to clearly disclose the hard-surfaced core, substantially as described. 55

5. A rug composed of woof strands each having a core of relatively bulky hard-surfaced fiber-like material and a relatively lighter open spiral winding of fluffy wool-like material outstanding from and bearing 60 upon the hard-surfaced fiber-like core, and a series of warp strands of relatively thin cord binding together the woof strands and holding the wool-like wrappings against displacement, the turns of the winding being spaced apart to clearly disclose the hard-surfaced core, substantially as described. 65

6. A rug composed of woof strands each having a core of relatively bulky hard-surfaced fiber-like material and a relatively lighter open spiral winding of fluffy wool-like material outstanding from and bearing 70 upon the hard-surfaced fiber-like core, and a series of warp strands of relatively thin cord binding together the woof strands and holding the wool-like wrappings against displacement, the rug having a stencil pattern imprinted upon its surface and impregnating the exposed portions of the fiber cores, the turns of the winding being spaced apart to clearly disclose the hard-surfaced core, substantially as described. 75

PHILIP C. WAITE.
